UNITED STATES PATENT OFFICE.

FRANK S. DIMON, OF BOURBON COUNTY, KANSAS.

WAGON-IMPLEMENT.

SPECIFICATION forming part of Letters Patent No. 243,865, dated July 5, 1881.

Application filed January 4, 1881. (No model.)

To all whom it may concern:

Be it known that I, FRANK S. DIMON, a citizen of the United States, residing in the county of Bourbon and State of Kansas, have invented certain new and useful Improvements in Tire-Tightener, Wrench, and Wagon-Pin; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The object of the present invention is to provide a device which can be used for connecting the double-tree to the tongue or shafts of a wagon, for expanding the felloes of a wheel so as to enable washers to be fitted on the spoke-tenons for the purpose of tightening the tire, and as a nut-wrench for general use on the nuts about a wagon.

20 The invention consists in the construction and combination of the parts, which will be hereinafter more fully described, and then set forth in the claim.

25 In the drawings, Figure 1 exhibits my device when used as a wagon-hammer for connecting the double-tree to the tongue. Fig. 2 shows the device in position for expanding the felloes of a wheel. Fig. 3 is a sectional view of the device.

30 The letter A designates a head or block, which is constructed or provided with two vertical plates or flanges, B, that project beyond one of the faces of said head, so as to form rigid wrench-jaws and spoke-clamps. A small plate, C, projecting horizontally from the upper end of the head A, serves, in connection 35 with a movable plate, D, sliding on the front face of said head, as a wrench for turning the nuts of the felly-clips, or other small nuts on a wagon. The upper end of the plate D is bent at right angles to the main portion of said 40 plate to form the movable jaw proper, and the lower end of said plate is turned in an inward direction, and is made forked or provided with a slot for receiving the pin or bolt E. The main portion of said bolt is made cylindrical, 45 and serves to connect the double-tree to the tongue, as is shown in Fig. 1. The bolt, above 50

the point of connection with the sliding plate or jaw, is formed into a screw-threaded shank, F, which fits into an internally-threaded bore or socket, G, made in the head A. A collar, H, and a circumferential groove made in the bolt, below the same, retain the forked or slotted end of the plate D. A vertical slot, I, in said plate, and a screw or pin, J, projecting from the block A, serve to guide and steady 55 the movement of said plate.

When the device is used as a tire-tightener, or more properly for expanding the felloes of a wheel, to enable washers to be fitted on the spoke-tenons, the lower end of the bolt E is 60 rested upon a block placed upon the hub of the wheel, while the plates or flanges B receive between them one of the spokes of the wheel.

65 The device having been applied in the manner described, the bolt or pin E is turned so 70 that its screw-threaded stem will work in the threaded bore of the head. This will cause the latter to press against the felly and expand or raise the same so as to expose the tenons of the spokes. Suitable split washers can now 75 be applied to said tenons in the manner and for the purpose already stated.

80 The bolt or pin E can be turned by means of a small pin inserted in the hole e made therein, or by other suitable means.

85 The plates or flanges B, which receive a spoke and prevent the lateral displacement of the device when in use as a tire-tightener, are sufficiently far apart to receive spokes of any ordinary size. These plates or flanges B are 90 preferably made slanting or inclined, so as to adapt the same to receive large and small axle-nuts, when the device is used as a wrench for turning the same.

95 I am aware that it is not broadly new to construct a wagon-hammer with wrench-jaws; but I am not aware that the bolt or pin portion of such a device has been made to answer the purpose of a handle for moving the jaws of the wrench.

100 It has also been proposed to expand the felloes of a wagon-wheel by devices acting on the principle of the jack-screw, and many expedients have been resorted to for retaining such devices in position on the wheel, but none involve the simplicity of construction, diversity of usage, and ease of operation of my device.

Having thus described my invention, what I claim as new, and desire to secure by Letters Patent, is—

The wagon-implement herein described, consisting of an internally screw-threaded head having parallel side jaws and rigid top jaw, the vertical pin or bolt, provided with an upper screw-threaded shank, and the plate or jaw

sliding on the head and connected with the bolt or pin, as and for the purpose set forth. ¹⁰

In testimony whereof I affix my signature in presence of two witnesses.

FRANK S. DIMON.
